DEEP WELL PUMP

Filed Oct. 9, 1929

UNITED STATES PATENT OFFICE

JOHN C. VROMAN, OF TULSA, OKLAHOMA, ASSIGNOR OF ONE-HALF TO C. P. SMITH, OF TULSA, OKLAHOMA

DEEP WELL PUMP

Application filed October 9, 1929. Serial No. 398,470.

This invention relates particularly to packing used on a traveling valve in an oil well or other deep well pump.

The practice has been to use a series of 5 leather or composition cups on the traveling valve to prevent the escape of oil between the valve and the wall of the working barrel. As an oil well two thousand feet in depth has a pressure of approximately one thousand 10 pounds at its bottom, it is obvious that these cups must be extremely tight and fit the working barrel perfectly in order to function properly. If the cups are extremely tight, they operate under considerable friction which is 15 objectionable. Moreover, due to wear, especially if the well is pumping part water, the cups decrease in diameter until oil leaks by them and then new cups must be substituted.

Another objection to the usual cups is that 20 they are made to fit a certain size working barrel and after the working barrel becomes worn even new cups might not fit it. This sometimes happens after a set of used cups has been withdrawn from the well and a set 25 of new ones installed therein with the usual delay and labor.

My invention overcomes these objections. I use lead as my packing and arrange it so 30 that it expands against the wall of the working barrel. Thus the working barrel may be slightly untrue or worn considerably and yet my packing will function perfectly. I also provide a follower to act upon the packing and keep it pushed out against the working 35 barrel, the force being exerted on the lead during the down stroke, when the pressure on the packing is a minimum.

As the lead wears and decreases in length, the follower remains closely adjacent thereto. 40 The increased capacity of the hydraulic chamber is filled with oil and the follower remains abutting the lead regardless of the size of the chamber or regardless of the length of the lead cup.

45 In some wells, the sand is sharp enough to "cut out" the cups every day, whereas when my improved valve is installed all difficulty along this line is overcome as the sand does not mar the surface of the lead or, if it does, 50 such cuts and the like are healed by the slight

but incessant action of the follower on the top of the lead cup.

I also provide a deflector whereby the sand particles are deflected outwardly and upwardly with the ascending stream of oil. 55

The invention will be hereinafter fully described and particularly defined in the appended claims.

In the accompanying drawings:

Figure 1 is a view of my traveling valve, 60 partly in elevation and partly in vertical section,

Figs. 2, 3 and 4 are horizontal sections on the lines 2—2, 3—3 and 4—4, respectively, of Fig. 1, 65

Fig. 5 is an enlarged view showing the position of the several members adjacent the fluid chamber just after the valve has started on its down stroke, and

Fig. 6 is a similar view showing the follower 70 in a lower position due to the shortening of the lead cup caused by wear and expansion.

The tube or body 1 has a shell 2 threaded onto its lower end and locked by means of 75 the set screw 3, the shell being formed externally with flat areas 4 to be engaged by a wrench or similar tool. Threaded onto the lower end of the shell 2 is the valve cage or cylinder 5 in the lower end of which is the 80 usual valve seat 6 to be engaged by the ball valve 7. Across the upper portion of the cylinder 5 is an integral web 8 with four holes 9 bored therein. This web forms an 85 abutment for the ball on the down stroke when the ball rises.

A fabric or composition washer 10 rests on the top of the shell 2 around the tube 1 and furnishes a soft seat for the steel ring 11 having an external annular groove 12. A 90 solid lead cup or packing element 13 rests on the top of the ring 11 and has a groove 14 formed in its inner face, while upper and lower grooves 15 are formed in the outer surface of the same. In operation, the lead is forced downwardly by the head 16 on the follower 17 and is thereby expanded outwardly 95 against the working barrel, indicated at 18. After the lead is worn out, it may readily be 100 removed from the working barrel by merely

pulling the sucker rods upwardly thus causing the extended lead to shear or tear off and collect in the groove 12 of the ring 11. This shearing is apt to occur after the valve has seen considerable service and the barrel, above the part in which the traveling valve is reciprocating, becomes corroded or "gypped".

The follower 17, which abuts the top edge 10 of the lead cup 13, is a cylinder encircling the tube 1 but spaced slightly therefrom, and it also encircles the reduced lower end 19 of the sleeve 20. The end 19 is spaced from the head 16 whereby an enclosed annular chamber 15 or recess 21 is formed, and a spring 22 is compressed in this recess. In its upper portion, the sleeve 20 is formed with an internal annular shoulder 23 adapted to abut a mating external shoulder 24 on the tube 1, the weight 20 being carried to the pump rods through the cage 25 and the sleeve 20. It will be noted that this is a direct connection with no play or lost motion, the pump or sucker rods being connected in the usual manner to the top 25 of the cage 25 which is threaded onto the upper end of the sleeve 20.

The sleeve 20 has a depending flange or follower sleeve 26 which may be threaded thereto, as at 27, and is longer than the inner flange or end member 19 in order that it may abut against the head 16 of the follower 17 and prevent mutilation of the spring 22. The members 19 and 26 form a tight running fit against the follower 17 and especially so 35 when the valve is submerged in oil. Similarly, the chamber 21 is more or less fluid tight.

The upper chamber 28 between the members 19 and 26 has a unique valve or cut-off 40 device leading thereto. This consists of a hole 29 through the sleeve 20 leading into the chamber 28, a groove 30 cut entirely around the interior of the sleeve at the inner end of said hole, and a hole 31 45 through the tube 1. The holes and the groove are in alinement when the valve is on its up stroke by reason of the shoulder 23 on the sleeve abutting the shoulder 24 on the tube. The sleeve and the tube also have holes 32 50 and 33 formed therethrough into which a pin may be inserted in order to assemble the parts by screwing the tube into the shell 2.

The cage 25 has the usual threaded neck 34 for connection with the lowermost pump 55 rod. This neck is bored out and a sand deflector 35 beaded therein, the deflector being an inverted cone.

When the valve is on the up stroke, the ball 7 is, of course, held to its seat and pressure or pull thereon is transmitted through the cylinder 5, shell 2 and tube 1 to the shoulder 24 where it is received by the shoulder 23 and transferred to the pump rods.

The end 19 of the sleeve 20 acts on the oil 60 which is entrapped in the chamber 21 and

force is transmitted through this oil to the head 16 of the follower 17. Oil is entrapped within the chamber or recess 28 on the down stroke but not until the sleeve 20 has slipped downwardly until the hole 29 therein is out of alinement with the hole 31 in the tube 1. Thus, the chamber becomes fluid tight and force may be transmitted through the fluid therein. When the holes 29, 31 slide past each other, a jar occurs upon the lead as the non-compressible fluid is entrapped in the chamber 28. The amount of this jar depends directly upon the size of the alined holes 29 and 31. The spring 22 tends to keep the follower head 16 adjacent the top of the lead cup 13, and said head may be beveled, as shown at 36, in order to more readily expand the lead cup.

As soon as the up pull on the sucker rods ceases, they and the valve tend to return 70 downwardly due to their weight. The downward movement is resisted by the fluid which is below the traveling valve passing upwardly therethrough, and the valve is thus subjected to two shocks, one acting upwardly, 75 the other downwardly. The upward shock is transmitted to the bottom of the lead cup through the valve cylinder 5, shell 2, washer 10, and steel ring 11.

The downward shock is transmitted to the 80 top of the lead cup, the opposed forces acting on the lead cup to distort it. As the cup cannot go inwardly, it expands outwardly. This expansion occurs when the valve is 85 on its down stroke and under a minimum 90 pressure which is obviously desirable as it allows the lead to readily expand.

The downward shock is transmitted to the 95 top of the lead cup through two separate systems. However, these systems act in parallelism. In both, the forces act upon the sleeve 20 through the cage 25 and thence 100 through the members 19 and 26.

It is to be understood that the term oil as 105 used in this specification includes all of the 110 fluids that are to be found and contended with in oil wells, such as water, gas, etc., as well as the hydrocarbons of oil proper.

Having thus described the invention, I 115 claim:

1. In a deep well pump, a tube having an external shoulder at its upper end and a small hole through the tube a short distance below the shoulder, packing supported on the tube, a follower having its lower end abutting the packing, the follower extending upwardly from the packing in spaced relation to the tube, a sleeve having an internal shoulder which fits underneath the shoulder on the tube, the sleeves extending downwardly within the follower, and a spring between the lower end of the follower and the lower end of the sleeve, said sleeve also having an interior groove and a hole in alinement with the small hole in the tube, and also having a de- 120 125 130

pending flange which slidably fits and surrounds the follower whereby an enclosed chamber is formed.

2. In a deep well pump a sleeve having an upwardly facing internal shoulder and a downwardly facing annular opening, a follower slidably mounted in said opening, packing below the follower, a tube having an external shoulder abutting the shoulder on the sleeve, and means on the tube to support the packing, said tube and sleeve having aligned holes therethrough to connect the circular opening with the interior of the tube to admit liquid from the tube thereto above the follower.

3. In a deep well pump, a tube, a sleeve encircling the tube and having a recess in its lower portion, means connected with the sleeve for lifting the same and the tube, a follower slidably mounted in the recess in the sleeve and cooperatively associated with the tube, and packing supported on the tube and receiving the impact of the follower, there being openings through the sleeve and the tube to admit fluid from the tube to the recess above the follower.

4. In a plunger having a central tube and packing thereon, the combination of means rigid with the tube at one end of the packing to support the packing, a follower slidably mounted on the tube at the other end of the packing, spring means to keep the follower snugly against the packing, and means slidably mounted on the tube to impinge against the follower and effect expansion of the packing.

5. In a deep well pump, a tube, packing thereon, means rigid with the tube at the lower end of the packing to support the packing, a follower slidably mounted on the tube at the other end of the packing, variable spring means to keep the follower tightly against the top of the packing, and impact means slidably mounted on the tube to impinge upon the follower and effect expansion of the packing.

6. In a deep well pump, a tube, packing thereon, means rigid with the tube at one end of the packing to support the packing, a follower slidably mounted on the tube at the other end of the packing, and hydraulic means cooperating with the follower to effect impact of the same upon the packing.

7. In a deep well pump, a tube, packing thereon, means rigid with the tube at one end of the packing to support the packing, a follower slidably mounted on the tube at the other end of the packing, hydraulic means cooperating with the follower to effect impact of the same upon the packing and auxiliary means for pushing the follower against the packing at all times.

8. In a deep well pump, a tube, packing thereon a sleeve encircling the tube, means to hold the sleeve from relative movement in one

direction, means to reciprocate the sleeve, said sleeve having a chamber or recess therein, and a follower slidably fitting into said chamber or recess and arranged to abut the packing for expanding the same.

9. A connection or take-up for a traveling valve consisting of a sleeve having a recess therein, a follower snugly fitting in the recess, and means for entrapping fluid in said recess to force the follower outwardly in the recess.

10. In a deep well pump, a tube, a packing of compressible metal on the tube, and a support for the packing secured on the tube below the packing and having an external annular groove in which excess of the compressible metal may be received.

In testimony whereof I affix my signature.
